Term of patent 14 years

Int. Cl. D9—04
U.S. Cl. D9—187

FIG. 1

FIG. 2

FIG. 3

FIG. 4

FIG. 1 is a three-quarter perspective view of a display tray embodying my new design, exemplary individual display items being shown in broken lines in position thereon;

FIG. 2 is a top plan view of the display tray, on an enlarged scale;

FIG. 3 is a front elevational view thereof; and

FIG. 4 is a cross sectional view taken along the line 4—4 of FIG. 2.

The dominant features of my design reside in the portion shown in full lines.

I claim:

The ornamental design for a display tray, as shown and described.
